UNITED STATES PATENT OFFICE

JAMES M. KENDALL, OF SCHENECTADY, NEW YORK, ASSIGNOR TO GENERAL ELECTRIC COMPANY, A CORPORATION OF NEW YORK

TRANSMISSION AND RECEPTION OF PICTURES

Application filed August 20, 1929. Serial No. 387,176.

My invention relates to the transmission and reception of pictures and the like, and has for its principal object the provision of an improved apparatus and method of operation whereby pictures may be transmitted and received without flicker and with a high degree of efficiency in the utilization of the light provided for illuminating the screen upon which the picture is produced.

10 In the past various types of picture transmitting apparatus including either a radio transmitter and receiver or a transmitter and receiver connected together by electrical conductors have been provided. Many of 15 these apparatus involved the use of means for producing a light dependent on the shade of the picture to be transmitted and means for converting such light into electrical impulses which must be reconverted to light at 20 the receiving station. Such apparatus has not proved altogether satisfactory in practical use for the reason that they are more or less complicated in structure and involve variable illumination and visibility of the 25 screen on which the picture is reproduced.

In accordance with my invention these difficulties are avoided by the provision of an improved light control screen which is continuously illuminated and involves a plurality of small movable sections or shutters which are readily controlled in accordance with the shade of the corresponding areas of the picture to be transmitted.

30 My invention will be better understood 35 from the following description when considered in connection with the accompanying drawings and its scope will be pointed out in the appended claims.

Referring to the drawings, Fig. 1 illustrates a picture receiving apparatus wherein my invention has been embodied; Figs. 2 and 3 show details of a light control screen which forms a part of the apparatus illustrated by Fig. 2; and Fig. 4 illustrates certain details 40 in the electrical connections by which the operation of the light control screen is controlled.

The apparatus illustrated by Fig. 1 includes a light control screen 10 which is 45 interposed between a light source 11 and the

picture receiving member 12 and is controlled in accordance with the signals received through a radio receiver 13. Suitable lenses 14 and 15 are interposed between the light source 11 and the screen 10 and between the screen 10 and the picture receiving member 12. As will hereinafter appear more fully, the operation of the light control screen 10 is controlled by means of a contact device 16 which may be driven by a motor 17. Capacitance elements 18 are connected to the receiver 13 in shunt with the movable and fixed elements of the screen 10 for intensifying the effect of the capacitive coupling between these members.

The screen 10 comprises a plurality of movable elements 19 which are pivoted at 20 and form one plate of an electrical condenser, the other plates of each condenser being one of the members 21. The condenser plates 21 are mounted on and electrically insulated from the members 22 which are supported by end supports 23. The condenser plates 21 are electrically insulated from the rest of the light control screen and are connected to different segments of the contact device 16.

Referring more particularly to Fig. 4, it will be observed that the condensers 18 are arranged to be connected to the radio receiver 13 through the contact device 16, each condenser 18 being connected to one segment of the contact device in parallel with a condenser formed by one pair of the plates 19 and 21. Any suitable means such as a motor 17 may be provided for driving the contact device in synchronism with the picture scanning and transmitting apparatus.

The small condenser plates 19 may be made of thin aluminum, gold leaf or the like, and are so arranged that they assume a position dependent on the charge imparted to them through the particular contact device segments with which they are connected.

The operation of the apparatus will be readily understood if it be assumed that each of the small movable condenser plates 19 represents a unit area of the picture and each row of the plates 19 represents a row or line of unit or elementary picture areas. Under these conditions the condenser plates 19 are

successively connected to the radio receiver 13 through the contact device 16 and successively receive electrical charges which are dependent upon the shade of that part of the picture to which the condenser plate corresponds. Due to these charges the plates 19 are moved more or less toward the cooperating condenser plates 21. Thus if the condenser plate corresponds to a white part of the picture the charge it receives is comparatively large. It is moved comparatively close to its cooperating plate 21 and admits a comparatively large amount of light from the light source 11 to the picture receiving member 12. If the plate 19 corresponds to a darker part of the picture however, it is moved through a smaller angle and permits a reduced amount of light to be projected on the member 12, the voltage applied through the radio receiver 13 being at each instant dependent on the shade of the particular elemental arc being scanned at that time.

It will of course be understood that the brush of the contact maker 16 is rotated synchronously with the signals received. As the brush passes each segment, it charges the corresponding condenser 19-21 almost instantly to a potential dependent upon the signal received. The condenser holds its charge and remains at practically the same potential until the brush passes over the distributive segment again. If there is no motion in the part of the picture corresponding to the movable plate of the condenser, the movable plate thus remains stationary and the light projected on the part of the receiving member which it controls is unchanged. If the part of the picture corresponding to the particular plate 19 has moved, the potential applied to the condenser 19-21 is changed and more or less light is projected on the part of the receiving member which it controls, the amount of light of course depending on whether the charge has increased or decreased.

As will be readily understood by those skilled in the art, the use of the improved light controlled screen is advantageous in that it permits the use of a very intense source of illumination and may be utilized to produce clearly defined pictures of any desired size. The small shutters or condenser plates 19 are not required to respond faster than in the order of 1/24 of a second, and of course do not have to move that often when the corresponding part of the picture remains stationary, but remain in the same position so long as no movement occurs in the corresponding part of the picture. Other advantages are that flicker is completely absent and that the light is used very efficiently.

The embodiment of the invention illustrated and described herein has been selected for the purpose of clearly setting forth the principles involved. It will be apparent,

however, that the invention is susceptible of being modified to meet the different conditions encountered in its use and I therefore aim to cover by the appended claims all modifications within the true spirit and scope of my invention.

What I claim as new and desire to secure by Letters Patent of the United States is:

1. A picture producing apparatus comprising a light control screen including a plurality of electro-statically controlled pivotally mounted shutters, means for projecting light through said screen, and means for causing said shutters to assume positions of light interception dependent on the shade of the picture to be produced. 75

2. A picture producing apparatus comprising a light control screen provided with a plurality of electro-statically controlled pivotally mounted shutters, a picture receiving member, means for causing said shutters to assume positions dependent on the shading of the picture to be produced, and means for projecting light through said screen upon said picture receiving member. 85

3. A picture producing apparatus including a light control screen provided with a plurality of electro-statically controlled pivotally mounted shutters, a picture receiving member, a source of illumination arranged to project light through said light control screen upon said picture receiving member, a device for receiving signals dependent on the shading of the picture to be produced, and a contact device arranged to cause said shutters to be operated in accordance with said signals. 95

4. Picture producing apparatus including a screen comprising a plurality of pivotally mounted condenser plates forming shutters arranged to variably intercept the passage of light through the screen, and means for causing said plates to assume positions dependent upon the shading of the picture to be produced. 105

5. Picture producing apparatus including a picture receiving member, a source of light, a screen therebetween comprising a plurality of pivotally mounted condenser plates forming shutters arranged to variably intercept the passage of light through the screen, and means for charging said plates to cause them to assume positions dependent upon the shading of the picture to be produced. 115

In witness whereof, I have hereunto set my hand this 19th day of August, 1929.

JAMES M. KENDALL.
